UNITED STATES PATENT OFFICE

JOHN F. WHITE, OF CHICAGO, ILLINOIS, ASSIGNOR TO HARRY B. STAVER, OF CHICAGO,
ILLINOIS

STARTING CAGE FOR RACING ANIMALS

Application filed February 9, 1927, Serial No. 166,942. Renewed May 28, 1932.

My invention concerns advancements in the construction of door or gate releasing means for compartments or spaces accommodating racing dogs in which they are housed preliminary to their release for participation in the race.

One object of the invention is to provide a structure of this character, which is simple in design, which operates effectively and efficiently, and which can be manufactured at relatively small expense.

To permit those skilled in this art to fully understand this invention both from structural and functional standpoints, desirable and preferred embodiments of the same have been illustrated in the accompanying drawing forming a part of this specification and throughout the several views of which for simplicity like reference characters have been employed for the same parts.

In this drawing:

Figure 1 is a fragmentary front elevation of the improved starting cage;

Figure 2 is an enlarged elevation of one of the chains showing one of the links capable of adjustment to vary its length;

Figure 3 is a fragmentary plan view of a portion of the structure shown in Figure 1;

Figure 4 is a fragmentary plan view on an enlarged scale of a part of the door-operating mechanism;

Figure 5 is a horizontal section on an enlarged scale through the hinge portions of two adjacent doors; and

Figure 6 is a fragmentary horizontal section illustrating the locking means for the doors.

Referring to this drawing, it will be seen that the multiple-compartment starting cage has back doors 10, a bottom wall 11, and a top wall 12, its several, dog-housing compartments being supplied at the front of the structure with a plurality of doors 13, 14, 15, 16, etc. arranged in pairs, as shown, one door being employed for each cage.

In order that the animals accommodated in such cages may view the race-course, the lower portions of such doors are preferably supplied with wired glass affording the view indicated.

Each such door at one upright edge has a vertically-arranged hinge-shaft 17 journaled at the top and bottom of the cage and each door also has a pair of upper and lower metal straps 18 bent at 19 around the corresponding hinge-shaft, as shown in Figure 5, and extending across the front and back faces of the door, being securely fastened to the latter by rivets 21 and similarly secured to the hinge-shaft by pins or rivets 22, whereby each door is properly mounted on its hinge-shaft.

As is clearly shown, the hinge-shafts of two adjacent doors are arranged close together and the top ends of such shafts are bent to form diverging arms 23 and 24 which are connected by coiled springs 25 to a bracket or plate 26 on the back of the top portion of the structure.

Obviously, these springs, if permitted to act, will quickly swing all of the doors to open position thus releasing the caged animals ready for joint participation in the race.

To hold the doors closed with the dogs confined in their cages or compartments, until it is desired to open them to free the animals, a plurality of vertically-slidable locking-bars 29, 29 are provided to overlap the protruding ends of the hinge-straps 18 which are accommodated in recesses 28, 28 in the upright members 27 between the pairs of doors and also at the outer sides of the end cages.

These bars 29 are slidably mounted in place by screw and slot connections 31, 31 and they have properly positioned recesses 32, 32 in their edges designed to release the bars 18 and their doors when they are raised into register with the ends of the former, all as will be readily understood.

All of such bars 29, at their upper ends, are connected by chains 33, each having a link 34 adjustable as to length, to arms 35 fixed on a shaft 36 oscillatory in bearings 37 and disposed lengthwise the row of cages, 95 at the top thereof, such shaft at one end having an appropriate operating handle 38.

When all of the doors have been closed and locked in that position by the descent of the bars 29, they will be retained in such 100

condition thus confining the dogs in their several adjacent cages.

When the right time arrives for releasing the animals, the operator rocks the shaft by means of its handle lifting or elevating the bars 29 and freeing the doors which swing open quickly under the action of their springs, thus liberating the dogs which immediately share in the race.

10 If the chains are of equal length, the doors will open simultaneously, but if a handicap or time delay or impediment is to be imposed on one or more dogs, the answering chain or chains is or are made longer by 15 adjustment of the extensible link or links 34 and the associated cage door or doors will open correspondingly later and by this means a more even and uniform race can be had between dogs of different abilities.

20 In order to limit the movements of the doors during this opening action, each set of bent arms 23 and 24 is provided on the top of the structure with a fixed block or abutment element 39 against which they are 25 adapted to strike when the doors are fully open.

Many minor mechanical changes may be incorporated in the structures herein set forth without departure from the heart and 30 essence of this invention as defined by the appended claims and without the sacrifice of any of its material benefits and advantages.

I claim:

1. In an apparatus of the character described, a plurality of separate doors pivoted to swing forwardly in opening, spring means tending to swing the doors open, and a shiftably mounted bar arranged to overlap portions of the doors adjacent the free edges of the latter to prevent the doors from swinging open, said bar being shiftable into a position wherein it does not overlap said door portions, whereby to release the doors and permit the spring means to swing the latter open.

2. In an apparatus of the character described, a plurality of pairs of separate doors pivoted to swing forwardly in opening, said door pairs being so mounted that the free edges thereof are adjacent, spring means tending to swing the doors open, shiftably mounted bars arranged to overlap portions of the free edges of each door pair to prevent the same from swinging open, and shifting means connected to said bars to simultaneously shift the latter into a position wherein they do not overlap said door portions whereby to release said doors.

3. In an apparatus of the character described, a plurality of separate doors pivoted to swing forwardly in opening, spring means tending to swing the doors open, a shiftably mounted bar arranged to overlap portions of the doors adjacent the free edges of the latter to prevent the doors from swinging open,

and an oscillatory shaft connected with said bar to shift the latter into a position wherein it does not overlap said door portions.

In witness whereof I have hereunto set my hand and seal.

JOHN F. WHITE.
